H. KOPPERS

TUNNEL OVEN FOR BURNING CERAMICS AND THE LIKE

Filed Aug. 31, 1921

UNITED STATES PATENT OFFICE.

HEINRICH KOPPERS, OF ESSEN-RUHR, GERMANY, ASSIGNOR TO THE KOPPERS DEVELOPMENT CORPORATION, OF PITTSBURGH, PENNSYLVANIA, A CORPORATION OF PENNSYLVANIA.

TUNNEL OVEN FOR BURNING CERAMICS AND THE LIKE.

Application filed August 31, 1921. Serial No. 497,371.

To all whom it may concern:

Be it known that I, HEINRICH KOPPERS (assignor to The Koppers Development Corporation, a corporation of Pennsylvania), a citizen of Germany, residing in Essen-Ruhr, Germany, have invented a new and useful Improvement in Tunnel Ovens for Burning Ceramics and the like, of which the following is a specification.

10 This invention relates to a furnace plant for burning fireproof lime bonded blocks silica, dinas.

According to another invention of mine which relates to a furnace plant for burning 15 fireproof, more particularly lime bonded, blocks silica, dinas, in which a plurality of separate, intermittently operated burning chambers are arranged, to which the material preheated in the preheating channels 20 resembling a channel furnace, that is, continuously operated, is fed in succession and from which it is conveyed, after completed burning, into the likewise continuously operated cooling channels; in this furnace 25 two cooling chambers are conveniently assigned to each preheating channel to enable the cooling to proceed very gradually. A plant of this kind is particularly well adapted to make possible, in the burning of 30 lime bonded blocks, the conversion of the quartzite into cristobalite, which requires a long presence of the blocks in the burning chamber at high temperature, while on the other hand the cooling of the burnt blocks 35 has to be done quite carefully.

The invention relates to the development of such a plant in accordance with the leading idea of another invention of mine in which the cooling chamber and the furnace 40 chamber, which are operated in the manner of the channel furnace, descend on the whole towards the cooler ends, in such a manner that under the natural buoyancy therein, the air or the waste gases in said chambers 45 range themselves in layers of uniformly diminishing temperature. By the union of these two inventive ideas a burning furnace of practically very high perfection is obtained, because therein both the cooling and

the preheating procedures are fully controllable.

In the drawing accompanying this application an adaption particularly good for this purpose is illustrated, in which—

Figure 1 is a plan view of so much of a furnace plant as is necessary to an understanding of the invention, the latter being embodied therein.

Fig. 2 is a vertical sectional view on line A—B of Fig. 1.

Fig. 3 is a similar sectional view on line C—D of Fig. 1.

The separate burning chambers 18 are connected at their ends by the tracks 17 and 19 while the preheating channels 10 and the cooling channels 11 are arranged parallel with the length of the said chambers. The plant is of duplicate formation with right and left units, as obviously one half of the plant could serve alone for the carrying out 70 of the process. The burning furnaces 18 are placed so high that the preheating channels 10 and the cooling channels 11 assume the desired inclined position in their descent to the floor of the structure (Figs. 2 and 3). 75 The raw material to be burned is placed in the lower end of the preheating channels 10 where it is gradually brought up to the level of the track 17 and carried hence to the burning furnaces 18 by a sliding platform 16 which can pass along by the track 17 to the front of any furnace. The material passes through the furnaces 18 in a direction contrary to the direction of the arrows shown, all of the arrows indicating 80 the directions of the gases in the ovens, preheating channels and cooling channels. The burnt material is delivered from the ovens on the sliding platform 20 which runs on the tracks 19 and said platform 20 is conveniently provided with a fireproof hood for preventing cooling. The platform 20 brings the completely burned material to the upper 85 ends of the cooling channels 11, in which it slowly moves downwards. There are two cooling channels provided for each preheating chamber, and the speed of traversing the single carriages through the cooling chan-

90

nels is half as great as in the preheating chamber.

As a result of the described construction an exceptionally compact arrangement is obtained, since the preheating and cooling channels are always led respectively upward and downward along the sides of the burning furnace, and as the upper parts of said channels are located alongside the furnaces the upper parts of said channels will be heated by said adjacent furnaces and a circulation will take place within the channels in accordance with physical laws, i. e., the hotter air being at the top of channels will seek a lower level or region as it cools and as the air cools it will gradually circulate towards the lower ends of the channels. Therefore, in the preheating channels the material entering at the lower end will be come progressively hotter as it ascends in the channel, while in the cooling channels the hot or burnt material will be cooled progressively, as it enters the cooling channels 11 at the higher, hotter, end and will cool as it descends towards the lower, cooler, end. The furnaces 18 may be of any suitable construction and may be heated or fired independently of each other or of said channels 10 and 11. Moreover a very simple track equipment is required, which allows the conveyance of the carriages from the preheating channels to the burning furnaces and thence to the cooling channels in the most convenient manner for operation.

35 What is claimed is—

1. In a furnace plant for the described purpose, the combination of a plurality of burning chambers, continuously operated preheating chambers and cooling chambers for said furnaces inclined with respect to said furnaces so that the air or waste gases under their natural buoyancy descend therein uniformly as they diminish in temperature.

45 2. In a furnace plant for the described purpose, the combination of a plurality of elevated burning chambers, continuously operated preheating chambers and cooling chambers inclined downwardly from said burning chambers and extending parallel to the length of said furnaces, and means supplying said furnaces with material from said preheating chambers and means supplying said cooling chambers with material from said furnaces.

55 3. In a furnace plant for the described purpose the combination of a plurality of elevated burning chambers, a continuously operated preheating chamber inclined downwardly from said burning chambers, a plurality of cooling chambers inclined downwardly from said burning chambers, said chambers being disposed so that the upper ends are hottest and their temperature

diminishes progressively towards their lower ends.

4. In a furnace plant for the described purposes, the combination of a series of parallel burning chambers having front entrances and rear exits for the material, tracks extending along the fronts of said chambers, tracks extending along the rears of said chambers, tracks at the side of the chambers inclined upward to said front tracks, preheating channels enclosing said inclined tracks, tracks at the side of the chambers inclined downward from said rear tracks, and cooling channels enclosing said downward inclined tracks, said tracks being adapted for the travel thereon of cars carrying the preheating and cooling material.

5. In a furnace plant for the described purpose, the combination of a series of parallel burning chambers having front entrances and rear exits for the material, a track extending along the fronts of said chambers, more elevated tracks extending along the rears of said chambers, a track at the side of the chambers inclined upward to said front track, preheating channels enclosing said inclined track, a plurality of tracks at the side of the chambers inclined downward from each of said rear tracks, and cooling channels enclosing said downward inclined tracks, all of said tracks being adapted for the travel thereon of platforms carrying the material which is being preheated and the burnt material which is being cooled.

6. In a furnace plant for the described purpose, the combination of a plurality of elevated burning chambers; continuously operated preheating chambers and cooling chambers inclined downwardly from said burning chambers and extending parallel to the length of said furnaces, and means supplying said furnaces with material from said preheating chambers and means supplying said cooling chambers with material from said furnaces, said cooling chambers having twice the capacity of said preheating chambers.

7. In a furnace plant for the described purpose, the combination of a plurality of burning chambers, continuously operated preheating chambers and cooling chambers serving said burning chambers, said preheating and cooling chambers being inclined downwardly from said burning chambers and extending parallel to the length of said burning chambers, the upper portions of said preheating and cooling chambers being disposed alongside said burning chambers.

8. In a furnace plant for the described purpose, the combination of a plurality of burning chambers, continuously operated

preheating chambers and cooling chambers serving said burning chambers, said pre-heating and cooling chambers being inclined downwardly from said burning chambers and extending parallel to the length of said burning chambers, the upper portions of said preheating and cooling chambers being disposed alongside said

burning chambers, means supplying burnt material to the upper end of said cooling chambers and means receiving preheated material from the upper ends of said pre-heating chambers.

In testimony whereof, I have hereunto set my hand this 26th day of July, 1921.

HEINRICH KOPPERS.
